SERVER FOR ICE CREAM, POTATOES,
OR THE LIKE

Earl S. Prince and Robert MacDougall, Rock Falls, Ill., assignors to Prince Castle Manufacturing Div., Inc., Sterling, Ill., a corporation of Illinois

Application November 4, 1948, Serial No. 149,462

Term of patent 14 years

(Cl. D44—29)

To all whom it may concern:

Be it known that we, Earl S. Prince and Robert MacDougall, citizens of the United States, residing at Rock Falls, in the county of Whiteside and State of Illinois, have invented a new, original, and ornamental Design for a Server for Ice Cream, Potatoes, or the like, of which the following is a specification, reference being had to the accompanying drawing, forming a part thereof.

Fig. 1 is a side elevational view of a server for ice cream, potatoes or the like embodying our new design;

Fig. 2 is a top plan view of the server for ice cream, potatoes or the like shown in Fig. 1;

Fig. 3 is a front end view thereof; and

Fig. 4 is a rear end view thereof.

The characterizing features of our new design are shown in full lines in the drawing.

We claim:

The ornamental design for a server for ice cream, potatoes, or the like, substantially as shown and described.

EARL S. PRINCE.
ROBERT MACDOUGALL.
